(57) CLAIM

The ornamental design for a cup, as shown and described.

DESCRIPTION

FIG. 1 is a perspective view of a cup showing the new design.

FIG. 2 is a side view of the cup of FIG. 1.

FIG. 3 is a top view of the cup of FIG. 1.

FIG. 4 is a bottom view of the cup of FIG. 1; and,

FIG. 5 is another perspective view of the cup of FIG. 1.

The broken lines are for illustrative purposes only, and form no part of the claimed design.
